UNITED STATES PATENT OFFICE

HORACE FRANÇOIS ADOLPHE TURRETTINI, OF GENEVA, SWITZERLAND

APPARATUS FOR ELECTRIC COOLING

Application filed September 28, 1926, Serial No. 138,227, and in Germany October 8, 1925.

The object of the present invention is to provide an apparatus for the production of cold by the utilization of the phenomenon, known under the name "Peltier effect", whereby a cooling in portions of such apparatus is electrically produced.

In this method of producing cold by an electric current the cooling substance, consisting of a soldered joint between two conductors of different compositions, does not undergo any physical or chemical change. There is no movement of material. There are no movable parts. Moreover, such apparatus can be utilized in any region of temperature, that is to say, produce a cooling effect no matter what the original starting temperature.

Various devices have already been proposed for utilizing the Peltier effect or phenomenon. The arrangements which are described below provide the means of increasing considerably the refrigerating capacity obtainable from a utilization of the effect of this phenomenon. The following description may be readily understood by reference to the accompanying drawings, in which:

Fig. 1 is a longitudinal section through an embodiment of my invention;

Fig. 2 is a transverse section of an embodiment of my invention; and

Figs. 3, 4, 5 and 6 are views similar to Fig. 1 of modified embodiments of my invention.

The cold produced at the joints of the two electrical conductors are by the Peltier effect proportional to the intensity of the current. At the same time, as a result of the phenomenon known as the "Joule effect," the current produces, in the complete circuit, an amount of heat proportional to the square of its intensity. Finally the joints which alternate with the cold joints are heated as the result of what may be described as an inverse Peltier effect, the resulting heat being hereinafter called Peltier heat.

For utilizing the Peltier cold the cooling couples comprise two distinct regions, that in which the Peltier cold is concentrated and that in which the Joule and Peltier heats are dissipated into the surroundings.

In the cold region it is necessary to (1)

reduce as much as possible the Joule heat, which tends to counteract the Peltier cooling effect; (2) diminish the losses by thermo-conductance through the conductors, which losses diminish the amount of the lowering of the temperature at the cold joint; (3) avoid losses by radiation and convection.

In the hot region it is necessary to facilitate the radiation and the convection of the Joule and Peltier heats into the surrounding atmosphere and to avoid their transference by thermo-conductance and convection to the cold region.

In the region of the cold joints the two metals will have sections of substantially the same proportion as their resistances. This condition is essential in order to allow the employment of the best current intensity and diminish in the highest degree possible the production of Joule heat and the conductance of heat from the hot to the cold region whereby the amount of decrease in the temperature of the latter would be diminished. In the case of certain metals or alloys it is possible to increase or decrease, up to about 10%, the cross section of that of the two metals having the greater resistance, the total cross section of the couple remaining the same. By the use of the aforesaid arrangement it is possible to pass the optimum current through the thermo-couple and to obtain the maximum lowering of temperature at the cold joint.

The cold region of the couples is immersed in a liquid contained in a container thermally insulated from the surroundings (as shown in Fig. 1) or in a container housed in a cold chamber thermally insulated from the surroundings (as shown in Figs. 4 and 6).

The presence of the liquid around the cold region of the couples and in contact with the said region increases the heat capacity of the said region and retains the cold produced which, otherwise, would be lost to a great degree through the outer heat conductivity, i. e. the surrounding liquid serves as a heat insulator.

Figs. 1 and 2 show a couple having its two conductors formed from an alloy 2 of bismuth and antimony on the one hand and from anti-

mony 1 on the other hand, soldered together at their lower ends by a copper plate 6, the cross sectional areas of the two metal members of the couple being in the same proportion as their resistances, that is the bismuth and antimony alloy has a section about 4 times that of the antimony. The horizontal extensions at the top of the two conductors form together a disc in two unequal sectors, the greater part being of bismuth. These two sectors provided with holes 4 to increase the heat dissipation, carry terminals 7 and 8 respectively. The joint or couple and the adjacent part of the conductors dip into a liquid to be cooled contained in a Dewar flask 5. The terminals 7 and 8 are connected respectively to the positive and negative poles of a direct current generator, and a current is established proceeding from the bismuth to the antimony passing across the joint, which in being cooled by the Peltier effect lowers the temperature of the liquid. The Dewar flask constitutes the cooling chamber of the system.

The hot region of the couple can be immersed in a liquid bath the usual convection currents of which disperse the heat produced by the Joule effect and by the Peltier effect into the surrounding atmosphere. This arrangement can be seen in Fig. 3.

With a couple or a multiplicity of couples, all the joints of which are in the same plane perpendicular to the direction in which conductors extend one cannot even with the strongest couples obtain more than a certain lowering of temperature, amounting to 10° or 11°, below the surrounding temperature. This is explained by the losses due to the thermal conductivity across the conductors and by the fact that one cannot exceed a certain current density by reason of the generation of heat according to the Joule effect.

To obtain a greater cooling at the cold joints it is necessary to increase the length of the cold region of the couples and consequently to absorb the Joule heat over a greater length. To arrive at this result use is made of staggered auxiliary couples whose cold joints provide a cooling effect at the levels where they adjoin the portions of longer conductors.

In Fig. 3 it will be seen how the first bank of couples 1 and 2, forming a cylinder, is surrounded by a second bank 9 of shorter couples forming a tube of which the joints 10 stop at a certain distance from the joints 6 of the first bank. The conductors of bank 9 are themselves surrounded by a third bank of couples 11, the joints 12 of which stop at a certain distance from the joints 10 of the second bank, and so on.

There is thus formed a metallic group whose section increases with the height in a predetermined proportion so as to absorb the Joule heat at different levels, reducing the losses due to radiation (reduced to the mini-

mum by the insulating medium surrounding the cold region) and giving a number of cooling points capable of attaining a permanent state in a given time. The temperature decreases from the small to the large end of the group according to the laws of thermal conductivity.

Instead of forming definite stages the auxiliary couples may be made imperceptibly shorter and shorter by being formed as a spiral band wrapped round the central cylindrical group. The auxiliary cold joints can not only be placed at the outside of the group but also at the interior in order better to distribute the cooling points in the whole of the width of the group.

The insulating material 12 separating the couples can be a solid substance as shown in Fig. 3.

In certain apparatus for the purpose of distributing the temperatures, use may be made, in addition to the thermal conductivity, of the natural convection currents of liquids as in Fig. 4. In other types of apparatus diaphragms of insulating material 13 can be used as in Fig. 6 to separate the different liquid levels and prevent convection in the vertical direction; or the variation of density of the liquid with the temperature may suffice to maintain around the region at the lowest level the longest couple, that is at the lowest level, the region of greatest density and consequently the most cooled portion of the liquid (Fig. 4).

For other apparatus with a small number of stages one can use, as in Fig. 5, an insulating covering 14 for each stage. The shortest couples of a particular stage are immersed in a liquid surrounding the insulating wall of the cold chamber in which are immersed the couples of the lower stage. With this arrangement one can obtain with two stages a lowering of temperature amounting to 17° to 18° below that of the surrounding temperature.

By reversing the direction of current flowing through the conductors one can obtain heat at the joints where with the arrangements previously described cold is generally produced.

Having now described the invention, what I claim is:

1. Apparatus for electric cooling by the utilization of the phenomenon known as the Peltier effect which comprises a thermo-couple constituted of two different metallic parts, the cross section of said two metallic parts being substantially in the same ratio as their resistances, an electrical connection for joining the two metallic parts at their cold joint, and a connector secured to the free end of each of the two metallic parts whereby an external source of electricity can be connected to said thermo-couple for the production of a cooling effect.

2. Apparatus for electric cooling by the utilization of the phenomenon known as the Peltier effect which comprises a thermo-couple constituted of a conductor of an alloy of bismuth and antimony and a second conductor of antimony, the cross section of said two conductors being substantially in the ratio as their resistances, an electrical connection of copper for joining the two parts of the thermo-couple at their cold joint, and a connector secured to the free end of each of the two conductors whereby an external source of electricity can be connected to said thermo-couple for the production of a cooling effect.
- 5 3. Apparatus for electric cooling by the utilization of the phenomenon known as the Peltier effect which comprises a thermo-couple constituted of two different metallic parts the cross sections of said metallic parts being substantially in the same ratio as their resistances, an electrical connection for joining the two metallic parts at their cold joint, a vessel containing liquid into which said metallic parts dip, and a connector secured to the free end of each of the two metallic parts whereby an external source of electricity can be connected to said thermo-couple for the production of a cooling effect.
- 10 4. Apparatus for electric cooling by the utilization of the phenomenon known as the Peltier effect which comprises a thermo-couple constituted of two different metallic parts, the cross sections of said metallic parts being substantially in the same ratio as their resistances, an electrical connection for joining the two metallic parts at their cold joint, a vessel containing liquid into which said thermo-couple dips, a connector secured to the free end of each of the two metallic parts whereby an external source of electricity can be connected to said thermo-couple for the production of a cooling effect, and means for thermally insulating said vessel and said thermo-couple from the surroundings.
- 15 5. Apparatus for electric cooling by the utilization of the phenomenon known as the Peltier effect which comprises a multiplicity of closely adjacent thermo-couples constituted of different metallic parts and of different lengths which have cold joints, said cold joints being staggered at different levels so that the shorter thermo-couples have a cooling effect on the adjacent longer thermo-couples, the cross sections of the metallic parts of each of said thermo-couples being substantially in the ratio of the resistances of the parts constituting the thermo-couple, a vessel containing a fluid into which said thermo-couple dips, and connectors secured to the free ends of said thermo-couples whereby an external source of electricity can be connected to said thermo-couples for the production of a cooling effect.
- 20 6. Apparatus for electric cooling by the utilization of the phenomenon known as the Peltier effect which comprises a multiplicity of closely adjacent thermo-couples constituted of different metallic parts and of different lengths which have cold joints, said cold joints being staggered at different levels so that the shorter thermo-couples have a cooling effect on the adjacent longer thermo-couples, the cross sections of the metallic parts of each of said thermo-couples being substantially in the ratio of the resistances of the parts constituting each thermo-couple, a plurality of vessels containing a liquid and arranged at different levels for accommodating the cold joints of said thermo-couples, a receptacle surrounding all of the aforesaid parts, and connectors secured to the free ends of said thermo-couples whereby an external source of electricity can be connected to said thermo-couples for the production of a cooling effect.
- 25 7. Apparatus for electric cooling by the utilization of the phenomenon known as the Peltier effect which comprises a multiplicity of thermo-couples surrounding each other and constituted of different metallic parts having cold joints and free ends, the cold joints of the outermost thermo-couples being located at higher levels than inner ones and the cross sections of the metallic parts being substantially in the ratio of the resistances of the parts constituting each of the corresponding thermo-couple, a plurality of vessels containing a liquid and arranged at different levels for accommodating the cold joints of said thermo-couples, a receptacle surrounding all of the aforesaid parts, and connectors secured to the free ends of said thermo-couples whereby an external source of electricity can be connected to said thermo-couples for the production of a cooling or freezing effect.
- 30 8. Apparatus as set forth in claim 7 in which diaphragms of insulating material are interposed between and around the various vessels to divide the space within said receptacle into different stages.
- 35 In testimony whereof I affix my signature.
